MOTOR TRUCK INSTRUMENT PANEL

Theodore Ornas, Jr., Ronald N. Brunger, Charles B. McGrew, Jr., and Deo Lewton, all of Fort Wayne, Ind., assignors to International Harvester Company, a corporation of Delaware

Filed Oct. 22, 1965, Ser. No. 87,758

Term of patent 7 years

(Cl. D14—6)

FIGURE 1 is a perspective view taken from the front and one side of a motor truck instrument panel, showing our new design;

FIGURE 2 is an elevational view taken substantially along line 2—2 of FIGURE 3; and

FIGURE 3 is an end elevational view of the motor truck instrument panel embodying our new design.

The portions shown in broken lines on the drawing are included for illustrative purposes only.

We claim:

The ornamental design for a motor truck instrument panel, substantially as shown and described.
